CIRCUIT BREAKER

Filed April 29, 1919

UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

CIRCUIT BREAKER.

Application filed April 29, 1919. Serial No. 293,433.

To all whom it may concern:

Be it known that I, EDWARD B. Nowosiel-
ski, a citizen of the United States, residing
at Bloomfield, in the county of Essex and
5 State of New Jersey, have invented certain
new and useful Improvements in a Circuit
Breaker, of which the following is a speci-
fication.

This invention relates to a type of circuit
10 breaker to be used particularly in connection
with an ignition apparatus that is used
on an internal combustion engine. In the
past few years the rotative speed of such
engines has been gradually increased until
15 the problem of designing a circuit breaker
for the ignition circuit has become a serious
one. Where a large number of cylinders
have to be fired in rapid rotation, such as on
an airplane engine of the 8, 12 or 16 cylinder
20 type, the circuit breaker has to act very
rapidly if satisfactory results are to be
obtained.

It is the principal object of my invention
25 to provide a circuit breaker which will op-
erate exceedingly fast and consequently de-
liver from the ignition coil a maximum effect
at the spark plugs of the engine cylinders.

Another object of my invention is to pro-
30 vide a circuit breaker which is very simple,
easy and cheap to manufacture and one that
requires very little attention in operation.

Other and further objects will be apparent
35 to one skilled in the art after a study of the
attached specification taken in connection
with the accompanying drawings, wherein,

Figure 1 is an end view of an ignition
generator showing my circuit breaker in op-
erative position thereon.

Figure 2 is a view similar to Figure 1 of
40 the circuit breaker but with the parts in
open circuit position.

Figure 3 is a plan view of the movable
member of the circuit breaker.

Figure 4 is a side elevation of one of the
45 sections shown in Figure 3.

Figure 5 is an elevation of the other sec-
tion which cooperates with the section shown
in Figure 4.

Figure 6 is a sectional view of the bearing
50 carrying the sections shown in Figures 4
and 5.

Figure 7 is a view of a cam used for an
irregular firing engine, that is one firing at
irregular intervals.

55 Referring now to the details, wherein like

numbers refer to corresponding parts in the
various views, 1 illustrates a magneto having
a distributor block 2 adapted for firing an
eight cylinder engine. A cam 3 carried on
the driving shaft of the magneto is adapted 60
for regular order of firing or every 90 de-
grees. Mounted on the end of the ignition
generator 1 is a cam holder 4 in which is set
an oil wick 5 for lubricating the cam 3. 65
Mounted on the holder 4 but insulated there-
from is a contact block 6 carrying an adjust-
able contact 7. A bearing 8 having a hollow
portion 9 is carried on a stud suitably attached
to the holder 4. The bearing 8 is adapted 70
to carry a certain quantity of lubricant 75
which works its way out of the hole 10. Bear-
ing 8 is held on the stud by a spring 11
fitting over the knob 12. The movable mem-
ber of the breaker is made up of two sections
13 and 14. The section 13 is shown in ele-
vation in Figure 5 and preferably consists
of one metal piece bent over in a manner
clearly indicated in Figures 3 and 5, a con-
tact 15 being carried near the extremity of
the section 13. Section 14 is preferably 80
made up of a single metal piece having arms
or extensions 16 that lie between the sides of
the section 13 and extend over the bottom
portion thereof. The opposite end of the
section 14 carries a bumper 17 which, in the
form shown, is of the roller type but which
may be made up in any other suitable man-
ner. Around the central part of the section
14 is a spring 18 which in assembled pos-
ition is indicated in Figure 3. This spring 85
18 serves to normally hold the section 14 in
the position shown in Figure 1 and acts to
make this section follow very rapidly the
contour of the cam used whether it be of the
type shown in Figure 1 or that shown in 90
Figure 7. A resilient member, preferably in
the form of a spring 19, is carried by the
holder 4 in such a position that it is in line
with the contacts 15 and 7 when the section
13 is assembled as shown in Figures 1 and 2. 95

In the operation of my circuit breaker, it
will be noted that the two sections have cer-
tain independent movements one from the
other. The spring 19 serves to hold the sec-
tion 13 normally in such position that the
contacts 7 and 15 are securely closed thereby
producing a good contact and it will be ap-
parent that the tension of this spring hold-
ing the contacts closed is not conveyed under
this condition to the section 14 as in the usual 100
110

practice which relieves the wear on the bumper as well as on the cam and therefore there is less work to be performed by the cam acting on the bumper and the spring 18 is made in such a manner as to give just sufficient action to the section 14 as will make it rapidly follow the cam. It will be noted that the arms or extensions 16 when the breaker points are closed are spaced away, as indicated at 20, from the bottom of the section 13 so that the section 14 when it is operated on by the cam 3 is started in movement before the section 13 is moved and at the time the projecting arms 16 strike the section 13, section 14 has accelerated to its maximum velocity and in effect gives the section 13 a hammer blow thereby separating the contacts very rapidly. After the engaging nose of the cam leaves the bumper 17 the spring 18, as above explained, causes the section 14 to follow the cam and the initial start is given by the spring 19 assisting the spring 18.

The holder 4 is so constructed at the point 21 that most of the flat portion of the section 13 will engage the holder along the line 21 for the greater part of the length of the section 13 thereby providing a stop for the section 13 of large area which feature is advantageous. Since the spring 19 is preferably placed at the extremity of the section 13 it has large leverage thereon and therefore a relatively light spring may be used which gives an easier and quicker spring action than the spring ordinarily used in circuit breakers used for this work. A breaker constructed in two sections, such as mine reduces the inertia of the moving parts and the contacts do not rebound when the breaker is operated at high speeds and consequently a maximum spark results at the engine cylinders.

It will be apparent that the circuit breaker may be used in other arrangements and that the details of the various parts may be varied without departing from the spirit of my invention or the scope of the appended claims.

Having thus described my invention, what I claim is:—

50 1. In a circuit breaker, a stationary member carrying a contact, a movable member carrying a cooperating contact, said movable member being in two sections arranged in tandem, one of said sections carrying said 55 cooperating contact and the other a bumper, means for normally holding said contacts together, a cam for acting on said bumper to operate the section carrying said bumper and operative means connecting the two sections 60 so that the actuation of the one by said cam causes the actuation of the other for the purpose described.

65 2. In a circuit breaker, a stationary member carrying a contact, a movable member carrying a cooperating contact, said movable

member being in two sections arranged in tandem, one of said sections carrying said cooperating contact and the other a bumper, a spring acting on the section carrying said cooperating contact to normally hold it 70 against the stationary contact, a cam for acting on said bumper to operate the section carrying said bumper, and means including an overlapping extension of the last mentioned section for engaging the first section 75 to transmit motion from the cam thereto.

3. In a circuit breaker, a stationary member carrying a contact, a movable member carrying a cooperating contact, said movable member being in two sections arranged in 80 tandem, each section having a certain movement independent of the other, one of said sections carrying said cooperating contact and the other a bumper, resilient means for normally holding the section carrying the cooperating contact in such a position that said contacts are together, said second section having an extension overlapping the first section but normally arcuately spaced away from it, a cam for acting on the bumper to operate the section carrying it, to cause said extension to suddenly engage with the first section to open said contacts.

4. In a circuit breaker, a stationary member carrying a contact, a movable member carrying a cooperating contact, said movable member being in two sections pivoted on a common center, one of said sections carrying said cooperating contact and the other a bumper, a cam for acting on said bumper to move the sections carrying it and operative means connecting the two sections so that the actuation of the one by said cam causes the actuation of the other for the purpose described.

5. In a circuit breaker, a stationary member carrying a contact, a movable member carrying a cooperating contact, said movable member being in two sections pivoted on a common center, one of said sections carrying said cooperating contact and having resilient means associated therewith to normally hold said contacts together, the other of said sections carrying a bumper and having an extension overlapping the first section, resilient means for holding the second section normally in such a position that the extension is arcuately spaced away from the first section and a cam for acting on the bumper to move its section and said extension to cause 115 rapid opening of said contacts.

6. In a high speed circuit breaker, a relatively stationary member carrying a contact, a movable member arranged in two sections pivoted at a common center but capable of 125 independent movements, a contact for co-operation with the first mentioned contact carried by one section near its extremity and a resilient member acting on this section substantially opposite said contact to man-

ually hold the contacts in closed position, the other of said sections having an extension at one end and carrying a bumper at the other, a resilient member for normally holding the said section in such position that said extension is elevated above the first section and a cam for acting on the bumper whereby the said extension is caused to strike the first section a hammer blow to 10 quickly open said contacts as described.

7. In a high speed circuit breaker, a relatively stationary member carrying a contact, a movable member consisting of two sectional portions capable of independent 15 movements but pivoted on a common center bearing, independent resilient means for actuating each section in a given direction, a cam for operating one of said sections in opposition to one of said resilient means, a 20 contact for cooperation with the first mentioned contact but carried by the other of said sections and actuating means on the cam operated section for operating the contact carrying section in opposition to the 25 other of said resilient means for the purpose described.

8. In a high speed circuit breaker, a relatively stationary member carrying a contact, a movable member consisting of two sectional portions capable of independent 30 movements but pivoted on a common center bearing, independent resilient means for actuating each section in a given direction, a cam for operating one of said sections in 35 opposition to one of said resilient means, a contact for cooperation with the first mentioned contact but carried by the other of said sections said resilient means for operating said contact carrying section being disposed in alignment with both said contacts 40 while the resilient means for the cam operated section is supported on said common center bearing and actuating means on the cam operated section for operating the contact carrying section in opposition to the 45 resilient means associated therewith.

9. In a high speed circuit breaker, a relatively stationary member carrying a contact, a movable member consisting of two sectional portions capable of independent 50 movements, a rotating cam for operating one of said sections, a spring for causing this section to follow the contour of the cam in its rotation, a contact for cooperation with the first mentioned contact but carried by 55 the other of said sections and a spiral spring acting in alignment with said contacts for holding said last mentioned section normally in such a position that said contacts are closed. 60

10. In a circuit breaker, a stationary member carrying a contact, a movable member consisting of two sections, one of said sections carrying a bumper and having projections extending over the other of said 65 sections, a cam for acting on the bumper, a spring for causing said section and bumper to follow the movements of said cam, the other of said sections carrying a contact for cooperating with the stationary contact, a 70 spring for holding said contacts normally closed and for returning said sections to closed position after being acted on by the first section and a stop for the second section extending adjacent thereto for considerable of its length. 75

11. In a circuit breaker, a relatively stationary member carrying a contact, a compound movable member carrying a co-operating contact, said compound movable member being constructed in two parts, each capable of movement independent of the other, means acting on one of said parts to cause it to move the other of said parts to separate the contacts and a spring mounted in and acting in alignment with said contacts to bring the part of the compound member to a position to close the contacts together after they have been separated. 80 85

In witness whereof, I affix my signature.

EDWARD B. NOWOSIELSKI.
